[57] CLAIM

The ornamental design for a skate board scooter, as shown and described.

DESCRIPTION

FIG. 1 is a top perspective view of a skate board scooter showing my new design;

FIG. 2 is a bottom perspective view thereof;

FIG. 3 is a left side elevational view with the handle member removed and the protruding tubular elements shown partially in fragment; and,

FIG. 4 is a right side elevational view thereof shown partially in fragment with the handle member in a compact condition.
